UNITED STATES PATENT OFFICE.

AUBREY J. GRINDLE, OF CHICAGO, ILLINOIS, ASSIGNOR TO COMBUSTION ECONOMY CORPORATION, OF CHICAGO, ILLINOIS, A CORPORATION.

APPARATUS FOR BURNING POWDERED COAL.

1,315,719.

Specification of Letters Patent.

Patented Sept. 9, 1919.

Application filed July 7, 1916. Serial No. 107,980.

To all whom it may concern:

Be it known that I, AUBREY J. GRINDLE, a citizen of the United States, and resident of Chicago, county of Cook, and State of Illinois, have invented certain new and useful Improvements in Apparatus for Burning Powdered Coal, of which the following is a specification, and which are illustrated in the accompanying drawings, forming a part thereof.

The invention relates to apparatus for the use of powdered coal as fuel and has especial reference to the provision of improved means for obtaining a uniform, regulated delivery of the fuel, a uniform admixture of the fuel with the amount of air required for combustion and an effective delivery of the mixed air and fuel into the furnace. The object of the invention is to provide an efficient and economical apparatus of the kind described.

In the accompanying drawings,

Figure 1 is a general side view of apparatus embodying the features of improvement provided by the invention, some of the parts being shown in central section,

Fig. 2 is an enlarged detail plan sectional view taken on the line 2—2 of Fig. 1,

Fig. 3 is a sectional view taken on the line 3—3 of Fig. 2,

Fig. 4 is a detail longitudinal sectional view showing the parts illustrated in side elevation in Fig. 1, drawn to a larger scale,

Figs. 5 and 6 are sectional views both taken on the plane indicated by line 5—5 on Fig. 4, but showing the parts as viewed in opposite directions at said plane.

Fig. 7 is an enlarged detail side elevation partly in section showing a form of burner 40 which is preferably employed for introducing the mixed air and fuel into the combustion chamber of a furnace,

Fig. 8 is a detail plan view partly in section, the plane of the section being indicated by the line 8—8 on Fig. 7, and Fig. 9 is a detail sectional view taken on the line 9—9 of Fig. 1.

The powdered fuel is preferably supplied from a hopper, as 10. This hopper is desirably constructed with a trough shaped bottom section 11 having a delivery tube 12 at one end, and a feed screw 13 is located in the hopper section 11 and preferably extends entirely through the same to the outer end of the said delivery tube. In the construction

shown, the feed screw 13 is provided with multiple threads 14, and each of these threads is formed with an abrupt forward face 15 and a sloping rearward face 16. While each of the threads 14 extends continuously from end to end of the feed screw 13, the removal of the material from the hopper 10 will proceed more uniformly throughout the length of the hopper, if the threads 14 are of increasing depth, as they approach the discharge tube 12. This is conveniently accomplished while still maintaining the same external diameter throughout the length of the feed screw if the threads 14 are formed about a tapering core 17. As shown, the threads 14 and core 17 are cast integral, the latter being tubular to permit of the feed screw 13 being sleeved over a shaft 20.

The shaft 20 is extended through the wall 75 of the hopper section 11 at one end for the application of power thereto for driving the feed screw 13. For this purpose, a sprocket wheel 21 may be mounted upon the projecting end of the shaft. The other end of the shaft 20 extends beyond the end of the discharge tube 12 and crosses the chamber of a housing 22 which is applied to and covers the end of the discharge tube. As shown, the housing 22 has tapering sides and is extended below the discharge tube 12 for the connection therewith of the carrying air supply pipe 23 and a conveying tube 24. Preferably the lower end portion of the housing 22 is constructed to receive a contracted nozzle 25 for the carrying air supply pipe 23. This nozzle faces the inlet end of the conveying tube 24 and the air jet issuing therefrom serves to induce the flow of material from the chamber of the housing 22 into the conveying tube.

A coöperating fixed plate 26 and rotatable plate 27 serve for regulating the discharge of fuel by the feed screw 13 into the chamber of the housing 22. These plates 190 are preferably constructed with coacting ribbed faces 28 and 29. As shown, the plate 26 has a central opening 26^a of substantially the same size as the outside diameter of the feed screw 13 and this plate is secured 105 against the wall of the housing 22 upon the inside of the same in front of the said feed screw. The plate 27 is made in the form of a disk and is splined upon the shaft 20 to rotate therewith at a regulated distance 110.

from the plate 26. The opening between the plates 26 and 27 is adjustably varied by sliding the disk 27 upon the shaft 20. For this purpose a collar 30 having a plurality of radial arms 31 is fixed upon the shaft 20 adjacent the hub of the plate 27, and adjusting bolts 32 are extended through the plate 27 and into the arms 31 of the collar. The housing 22 has a removable cover plate 22^a to provide access to the adjusting bolts 32. If desired this cover plate may be removed during the operation of the device, in which case a current of air will be induced to flow downwardly through the 15 chamber of the housing 22 by the jet issuing from the nozzle 25.

The conveying tube 24 will usually enter the volume air supply pipe, as 33, a short distance from the furnace, indicated at 34, 20 as at an elbow 35. Under these circumstances any precipitation of the fuel in the pipe 33, beyond the elbow 35, is effectually prevented and a uniform admixture of the volume air with the fuel is insured if stationary inclined blades 36 are located in the pipe 33 at intervals between the elbow 35 and the furnace. As shown, the inclined blades 36 are arranged in pairs of sets 37, 38, the blades in the two sets of each pair being 25 oppositely inclined and three such pairs of sets being employed. By locating the oppositely inclined sets 37 and 38 of each pair adjacent the axis and the periphery of the pipe 33, respectively, and by oppositely 30 inclining corresponding sets of adjacent pairs, the matter traveling through the axial and peripheral portions of the pipe 33 will be oppositely whirled in reverse directions in rapid succession. When the blades 36 are provided the portion of pipe 33 adjacent the burner may be regarded as a mixing chamber and will be so referred to in some of the claims. However, notwithstanding the presence of the mixing blades, 35 the portion of the pipe 33 where they are located while serving as a mixing chamber is none the less a conveying tube.

The burner, as 39, is preferably constructed with a flaring mouth piece 40 of 50 oblong rectangular shape and with a tubular shank 41 which varies in shape throughout its length to fit the pipe 33 at one end and to connect with the smaller end of the mouth piece 40 at the other end. The mouth piece 40 of the burner 39 enters a correspondingly shaped opening 42 in one of the walls, as 43 of the furnace 34. While the mouth piece 40 of the burner and the opening 42 in the furnace wall are shown as being 55 of increasing size toward the furnace chamber, the discharge of air and fuel from the burner is preferably confined to a flat stream which is of reduced thickness, as compared with the diameter of the pipe 33. 60 This may be accomplished by the use of a

pair of swinging deflector plates 44, 45. As shown, each deflector plate 44, 45, is fixed upon a spindle 46 which extends through the side wall of the burner 39, at one end and is there provided with a crank arm 47 70 for turning the spindle to adjustably position the corresponding plate. To provide a convenient means for securing the deflector plates 44, 45 in angularly adjusted positions, each crank arm 47 is formed with a 75 curved slot 48 and a set screw 49 passes through this slot and enters a bracket lug 50 formed upon an adjacent part of the wall of the burner 39.

In some instances it will be desirable that 80 parts of the walls of the burner 39 and the deflector plates 44, 45, should be water cooled. This is readily accomplished with respect to the walls of the burner 39 by making the corresponding parts of these 85 walls hollow, as indicated at 51, and providing them with water inlet and outlet nipples, as 52, 53. The deflector plates 44 and 45, on the other hand, may be supplied with water through the spindles 46. As shown, 90 each spindle 46 is made tubular for a portion of its length adjacent each end, as indicated at 54, 55, and water supply and discharge pipes 56, 57, are connected with the two spindles at one end. A union 57^a, having a swiveled connection 58 with each spindle 46, serves to connect the two spindles at the other end. The deflector plates 44 and 45 are made hollow and their chambers, as 95 59, are constructed with baffles 60 and 61 to insure the circulation of water to that part of the chamber which is adjacent the outer end of the plate. Each chamber 59 communicates with the bores of the tubular end portions 54, 55 of the corresponding spindle 100 46, through port openings 62 and 63. This construction permits of the angular adjustment of the deflector plates 44, 45 without interfering with the circulation of water through the same. It will be observed 105 that both the depth and direction of the flame may be modified by the angular adjustment of the two deflector plates.

If the furnace 34 is to be used as a melting furnace, a part, as 61^a, of the furnace chamber adjacent the wall 43 serves as a combustion chamber and is preferably provided with an inclined floor 62^a which slopes toward the hearth 63^a. The slag or melted ash which results from the combustion of 110 the powdered coal thus drains onto the bath of molten metal and mingles with the slag which usually floats upon such a bath. To provide suitable baffles for the flame to impinge upon for maintaining the ignition, especially during the early part of the melting operation when cold metal is piled upon the hearth 63^a, a row of masonry piers 64 extending from side to side of the combustion chamber with openings 65 between the piers 115 120 125 130.

may be erected upon the floor 62^a adjacent the hearth 63^a. By reason of the openings 65 between the piers 64, the flow of slag from the floor 62^a on to the bath is not materially 5 interfered with.

It has been found desirable to mount the burner 39 at such an inclination that its axis is located upon a line with the adjacent corner of the pier 64 which is directly 10 in front of the burner. While only a single burner 39 is shown for simplicity of illustration it will be understood that as many burners will be employed as may be necessary to cover the furnace from side to side 15 and that a separate fuel feeding apparatus may be employed for each burner.

A supplemental air supply, introduced in a flat stream, as through a slotted opening 66 in the top of the furnace may be employed for depressing the flame over the 20 hearth. Preferably the opening 66 takes the form of a continuous slot extending from side to side of the furnace. When air under pressure is introduced through the 25 opening 66 the volume air introduced through the pipe 33 may be reduced in amount. While the depression of the flame by the introduction of a flat stream of air through the opening 66 serves to sweep the 30 slag along the bath toward the remote end of the furnace, the oxidation of the bath may be effectively controlled by a suitable proportioning of the total amount of air employed to the amount of fuel.

To permit of the nozzle 25 being adjusted toward and away from the inlet end of the conveying tube 24, it may be slidingly entered in the corresponding side wall of the housing 22. As shown the outer end of 40 the nozzle 25 is formed with an outstanding annular flange 67 and adjusting screws 68 are extended through this flange and into the adjacent side wall of the housing 22 for adjustably positioning the nozzle 25. The 45 gathering up of the powdered coal as it falls into the lower part of the housing 22, by the current of air entering the conveying tube 24, is facilitated if an annular series of port openings 69 are provided in the side wall of 50 the housing 22, about the nozzle 25. Air is thus drawn into the chamber of the housing 22, through the port openings 69 and mingle 55 with the air which is supplied through the pipe 23, as it enters the conveying tube 24.

When the furnace is largely filled with cold iron, ignition is more readily maintained if the deflector plates 44, 45 are adjusted to cause the flame to play upon the 60 floor 62^a of the combustion chamber 61^a. Later on in the operation, the employment of the deflector plates 44, 45, is not essential and when these plates are present, as shown, they will preferably be so adjusted that 65 their free ends are separated the full dis-

tance permitted by the depth of the mouth piece 40.

I claim as my invention:—

1. In an apparatus for burning powdered fuel, in combination, a burner, a tubular 70 mixing chamber delivering to the burner, volume and carrying air supply pipes delivering to the said mixing chamber and two sets of inclined blades located within the mixing chamber, the blades of the two sets 75 being oppositely inclined and the blades of one set being arranged in an annular series adjacent the wall of the mixing chamber and the blades of the other set being located within the space which is inclosed by the 80 said annular series of blades whereby the two sets of blades act simultaneously but independently upon different parts of the air and fuel current passing through the mixing chamber, the said different parts of the 85 air and fuel current being respectively located adjacent the axis of the mixing chamber and adjacent the wall of said chamber.

2. In an apparatus for burning powdered fuel, in combination, a burner, a tubular 90 mixing chamber delivering to the burner, volume and carrying air supply pipes delivering to the said mixing chamber, and a plurality of pairs of sets of stationary inclined blades located at intervals in the length of 95 the mixing chamber, the blades of the two sets of each pair being oppositely inclined, the blades of one set of each pair being arranged in an annular series adjacent the wall of the mixing chamber, the blades of the other set of each pair being located within the space which is inclosed by the annular series of blades of the same pair and the blades of the corresponding sets of adjacent pairs being oppositely inclined. 105

3. In an apparatus of the kind described, in combination, a hopper for powdered coal or the like having a discharge opening, a chambered housing covering the discharge opening of the hopper and extending below 110 the same, a feed screw operating within the hopper to deliver to its said opening, the spindle of the feed screw being extended through the hopper opening into the chamber of the said housing, a plate larger than 115 the hopper opening mounted upon the feed screw spindle to rotate therewith within the chamber of the said housing, the face of the plate coöperating with the face of the inside wall of the housing about the hopper opening to regulate the discharge of material through the said opening into the chamber of the housing, a jet burner, a conveying tube leading laterally out of the chamber of the housing at one side of the same below 120 the hopper opening and plate to the burner, and a blast jet entering the chamber of the housing at the opposite side of the same in line with the said conveying tube. 125

4. In an apparatus of the kind described, 130

4 in combination, a hopper for powdered coal or the like having a discharge opening, a chambered housing covering the discharge opening of the hopper and extending below the same, a feed screw operating within the hopper to deliver to its said opening, the spindle of the feed screw being extended through the hopper opening into the chamber of the said housing, a plate larger than the hopper opening mounted upon the feed screw spindle to rotate therewith within the chamber of the said housing; the face of the plate coöperating with the face of the inside wall of the housing about the hopper opening to regulate the discharge of material through the said opening into the chamber of the housing, a jet burner, a tubular mixing chamber delivering to the burner, a volume air supply pipe delivering to the mixing chamber, a conveying tube leading laterally out of the chamber of the housing at one side of the same below the hopper opening and plate and joining the volume air supply pipe in front of the mixing chamber, a blast jet for a supply of carrying air entering the chamber of the housing at the opposite side of the same in line with the said conveying tube, and two sets of inclined blades located within the mixing chamber, the blades of the two sets being oppositely inclined and the blades of one set being arranged in an annular series adjacent the wall of the mixing chamber and the blades of the other set being located within the space which is inclosed by the said annular series of blades.

5. In an apparatus of the kind described, in combination, a hopper for powdered coal or the like having a discharge opening, a chambered housing covering the discharge opening of the hopper and extending below the same, a feed screw operating within the hopper to deliver to its said opening, the spindle of the feed screw being extended through the hopper opening into the chamber of the said housing, a plate larger than the hopper opening mounted upon the feed screw spindle to rotate therewith within the chamber of the said housing, the face of the plate coöperating with the face of the inside wall of the housing about the hopper opening to regulate the discharge of material through the said opening into the chamber of the housing, a jet burner, a tubular mixing chamber delivering to the burner, a volume air supply pipe delivering to the mixing chamber, a conveying tube leading laterally out of the chamber of the housing at one side of the same below the hopper opening and plate and joining the volume air supply pipe in front of the mixing chamber, a blast jet for a supply of carrying air entering the chamber of the housing at the opposite side of the same in line with the said conveying tube, and a plurality of pairs of sets of sta-

tionary inclined blades located at intervals in the length of the mixing chamber, the blades of the two sets of each pair being oppositely inclined, the blades of one set of each pair being arranged in an annular series adjacent the wall of the mixing chamber, the blades of the other set of each pair being located within the space which is inclosed by the annular series of blades of the same pair and the blades of the corresponding sets of adjacent pairs being oppositely inclined.

6. In an apparatus of the kind described, in combination, a chambered housing having two inlet and one outlet opening, a feed screw delivering to one of the inlet openings from without the chamber of the housing, the spindle of the feed screw being extended through the said opening into the chamber of the housing, a plate larger than the last mentioned inlet opening of the housing mounted upon the feed screw spindle to rotate therewith within the chamber of the housing, the face of the plate coöperating with the face of the inside wall of the housing about the said inlet opening to regulate the discharge of material through the said opening into the chamber of the housing, a jet burner, a conveying tube leading from the outlet opening of the housing to the burner and means for inducing a blast of air to enter the chamber of the housing through the other inlet opening and pass through the chamber of the housing and conveying tube to the burner.

7. In an apparatus for burning powdered fuel, in combination, a combustion chamber, a burner housing having a contracted throat and a flaring mouth entering the combustion chamber, a pair of independent swinging plates mounted within the flaring mouth of the burner housing, each plate being hingedly connected with the wall of the burner housing at its said throat, and volume and carrying air supply pipes delivering to the burner housing from without the combustion chamber.

8. In an apparatus for burning powdered fuel, in combination, a combustion chamber, a burner housing having a contracted throat and a flaring mouth entering the combustion chamber, a pair of independent chambered swinging plates mounted within the flaring mouth of the burner housing, a pair of tubular trunnions for each of the said plates journaled in the walls of the burner housing at its said throat and extending through the said walls, the bores of the trunnions communicating with the chamber of the corresponding plate, water supply and discharge pipes connected to the two trunnions of each plate, and volume and carrying air supply pipes delivering to the burner housing from without the combustion chamber.

9. In an apparatus for burning powdered

fuel, in combination, a burner, a tubular mixing chamber delivering to the burner, an air and fuel supply pipe delivering to the said mixing chamber and two sets of inclined blades located within the mixing chamber, the blades of the two sets being oppositely inclined and the blades of one set being arranged in an annular series adjacent the wall of the mixing chamber and the blades of the other set being located 10 within the space which is inclosed by the

5 said annular series of blades whereby the two sets of blades act simultaneously but independently upon different parts of the air and fuel current passing through the 15 mixing chamber, the said different parts of the air and fuel current being respectively located adjacent the axis of the mixing chamber and adjacent the wall of said chamber.

AUBREY J. RINDLE.
